DESIGN FOR A DRESS ENSEMBLE

Marguerite Reirden Richardson and Eugenia
Staber, New York, N. Y.

Application April 26, 1939, Serial No. 84,580

Term of patent 3½ years

To all whom it may concern:

Be it known that we, Marguerite Reirden Richardson and Eugenia Staber, citizens of the United States of America, residing in New York city, in the Borough of Manhattan, county and State of New York, have invented a new, original, and ornamental Design for a Dress Ensemble, of which the following is a specification, reference being had to the accompanying drawings, forming part thereof, wherein,

The drawings are lined to represent the colors red, white, and blue.

We claim:

The ornamental design for a dress ensemble, substantially as shown, and described.

EUGENIA STABER.
MARGUERITE REIRDEN RICHARDSON.
